UNITED STATES PATENT OFFICE.

GEORGE KUNKLE, OF GRAND JUNCTION, COLORADO.

TRACK.

1,404,127.

Specification of Letters Patent. Patented Jan. 17, 1922.

Application filed May 10, 1921. Serial No. 468,400.

To all whom it may concern:

Be it known that I, GEORGE KUNKLE, a citizen of the United States, and a resident of Grand Junction, in the county of Mesa and State of Colorado, have invented a new and Improved Track, of which the following is a full, clear, and exact description.

This invention relates to improvements in tracks, an object of the invention being to provide a track for vehicles, which will eliminate the necessity of building expensive roads in inaccessible places.

Another object is to provide a track which is made in sections, which will conveniently accommodate motor driven vehicles, which can be quickly laid down and taken up.

A further object is to provide a track which will be particularly useful as a permanent traffic link in regions occupied by the extractive industries, such as mining, lumbering and quarrying, which will be useful in all places where the natural condition of the country makes road building expensive.

25 A still further object is to provide a track which will be useful for elevated road traffic in congested cities and which will have many other uses which need not be specifically pointed out in this application.

30 Still another object is to provide a track, which will increase the life of rolling stock, which will expedite deliveries and eliminate the exigencies of weather in overland transportation, and a track which will be simple and practical in construction, durable and efficient in use, and comparatively inexpensive to install and maintain.

With these and other objects in view, the invention consists in certain novel features 40 of construction and combinations and arrangements of parts as will be more fully hereinafter described and pointed out in the claims.

In the accompanying drawings:—

45 Figure 1 is a plan view of my improved track, illustrating a main track at a point where it connects with a turn-out track;

Figure 2 is an enlarged view in section on the line 2—2 of Figure 1;

50 Figure 3 is a fragmentary sectional view on the line 3—3 of Figure 1;

Figure 4 is a perspective view of the junction of one of the main tracks with the turn-out track; and

Figure 5 is a fragmentary perspective view illustrating a slightly modified form of track.

Referring in detail to the drawings, my improved track comprises a pair of track elements or rails indicated by the reference numeral 5, which are spaced apart and are held against spreading in a manner to be hereinafter described. The track elements or rails may be laid any convenient distance apart and are preferably gauged to accommodate the class of motor vehicles most commonly employed.

Referring now specifically to the construction of each rail, it will be seen that each rail comprises a pair of parallel side bars 6 which conveniently support between them a series of concavely bowed wheel supporting members 7, connected at their opposite ends to the bars 6. The bars 6 include at their lower edges side flanges 8, which rest upon the ground and the flanges 8 are integral with perforated lugs 9 adapted to receive any preferred form of securing device 10 for holding the rails to the ground, or to a supporting structure (not shown). The outer side bar 6 of each rail includes integral upstanding lugs 11, which support a guard rail 12. The guard rails 12 positively prevent the wheels of a vehicle from accidentally rolling off the track.

85 The concave wheel supporting elements 7 may be surfaced at their intermediate portion with asphalt or similar material 13, so that a vehicle passing over the track may firmly grip the traction surface 13. I do not wish to limit myself either to the use of this surfacing material, or to any particular method of applying the material to the wheel supports when it is used. In the drawings, I have shown 90 the surfacing as super-imposed upon the wheel supports, but it will be apparent that these supports might be recessed and any suitable plastic material molded into the recess and hardened.

100 Adjacent each end, the side bars 6 are provided with openings such as 14. Hooked links 15 are engageable in the openings. A pair of such links engage in the adjacent openings in the adjacent ends of the side bars 6 and are both pivoted to the end of a stay rod 16. The stay rods 16 are screw threaded at their inner ends and are operated

by a turn buckle 17 for adjusting the rails 5 and preventing spreading thereof, as will be readily understood.

In Figure 1, I have illustrated a turn-out track 18 communicating with the main track. The side bars 6 of the turn out track which are adjacent the side bars of the main track are preferably made integral with these last mentioned side bars to provide a 10 frog such as 19, which lends strength to the junction of the two tracks. At the point where the main track joins or crosses the turn-out track, the two tracks will have a certain amount of traction surface in common 15 as will be readily understood, and in order to facilitate the steering of a machine from the main track into the turn-out track, the wheel supports 20 which make up this common traction surface include a flat intermediate portion instead of a rounded one. They may, however, be surfaced in the usual 20 manner, as indicated at 21.

In Figure 5, I have illustrated a modified form of rail which includes the usual side 25 bars 22, concave wheel supports 23 and guide rail 24. In this instance, the wheel supports are spaced some distance apart and serve as cradles for longitudinal slats 25. The slats 25 may be treated in any appropriate manner to provide a frictional traction surface.

Although I have illustrated certain of the preferred embodiments of my invention, it will be apparent that the particular method 35 of connecting a main track with a turn-out track, is immaterial and that various slight changes and alterations might be made in the general form and arrangement of the parts described without departing 40 from the invention and hence I do not wish to limit myself to the precise details set forth, but shall consider myself at liberty to make such slight changes and alterations as fairly fall within the spirit and scope of 45 the appended claims.

I claim:

1. A track of the character described, comprising a pair of track elements spaced apart, each of said elements including pairs of 50 side bars and cross pieces connecting said side bars.

2. A track of the character described, comprising a pair of track elements spaced apart, each of said elements including pairs of side bars, cross pieces connecting said side bars, traction surfaces supported on 55 said cross pieces.

3. A track of the character described, comprising a pair of concave track elements spaced apart, each of said elements comprising pairs of side bars and concave bowed members connecting the side bars. 60

4. A track of the character described, comprising a pair of track elements spaced apart, each of said elements including pairs of side bars, cross pieces connecting the side bars and cementitious material supported on the cross pieces providing a traction surface. 65

5. A track of the character described, 70 including a pair of parallel track elements, each element comprising longitudinal side bars, concavely bowed cross pieces and a traction surface supported upon the cross pieces. 75

6. A track of the character described, including a pair of parallel track elements, each element comprising longitudinal side bars, concavely bowed cross pieces and a traction surface supported upon the cross pieces, each of said side bars including at 80 their lower edges laterally extending flanges, and means for securing said flanges upon a supporting surface.

7. A track of the character described, 85 including a pair of track elements, each element comprising a pair of parallel side bars, concavely bowed cross pieces connecting the side bars, said cross pieces forming cradles, longitudinal slats supported on the 90 cradles and cooperating to form a traction surface.

8. A track of the character described, including pairs of parallel track elements located end to end, the adjacent ends of the 95 elements having openings therein, links engageable in the openings of the adjacent elements, stay rods pivotally connected to the pairs of links and a turn buckle for operating the stay rods.

GEORGE KUNKLE.
